UNITED STATES PATENT OFFICE.

HENRY FRAZEE, JR., OF OBERLIN, OHIO, ASSIGNOR TO TROY LAUNDRY MACHINERY CO. LTD., OF CHICAGO, ILLINOIS, A CORPORATION OF NEW YORK.

DEODORIZER.

Application filed June 16, 1919. Serial No. 304,559.

To all whom it may concern:

Be it known that I, HENRY FRAZEE, Jr., a citizen of the United States, residing at Oberlin, in the county of Lorain and State 5 of Ohio, have invented certain new and useful Improvements in Deodorizers, of which the following is a specification.

This invention is designed primarily as a means for thoroughly aerating clothing or 10 other goods for the purpose of removing therefrom any odor remaining therein after they are subjected to the gasoline cleaning process; but the apparatus also serves the purpose of removing dust and lint from the 15 material.

The invention consists in a rotary drum having one of its walls (preferably its cylindrical wall) reticulated to permit the flow of air therethrough, with a conduit for conducting air to the interior thereof (preferably through a hollow trunnion), and with 20 baffles distributed around the interior of the drum; said baffles being in the form of brushes or groups of bristles, whereby they 25 not only assist in tumbling the goods but brush the surface thereof in a manner to remove lint and dust therefrom and leave the nap of the goods in better condition for aeration. The bristled baffles are preferably left 30 free to rotate under the action of the goods rubbing against them.

The invention will be fully understood upon reference to the accompanying drawings, in which—

35 Figures 1 and 2 are, respectively, a side elevation and a front elevation of a deodorizer embodying the several features of the present invention.

Figure 3 is a vertical section on the line 40 3^x—3^x of Figure 2; and

Figure 4 is an axial section of the drum.

1 represents a casing having doors 1^a affording access to the interior thereof, and 2 represents a drum rotatably mounted in 45 said casing through the medium of trunnions 3; said drum having solid heads 2^a, a reticulated cylindrical wall 2^b, and a door 2^c, the latter affording access to the interior of the drum when opened through the doors 1^a.

50 One of the trunnions 3 is made hollow for the purpose of providing a port 3^a, with which is made to register a conduit 4 which leads from a heating chamber 5 so that air

forced into the chamber 5, as, for instance, through a fan 6, will be heated and driven 55 into the drum and made to circulate through the goods therein, escaping through the reticulated periphery of the drum into the casing 1, whence it may escape.

Within the drum 2 are baffles which assist 60 in tumbling the goods in the drum. These baffles serve more than the mere tumbling purpose; they are in the form of brushes or group of bristles 7, preferably free to rotate, and they stir up the nap of the goods, removing lint and dust therefrom and leaving the goods in better condition for penetration 65 of the air which is to remove any remnant volatile and odorous cleaning solution 70 therein.

The drum 2 may be revolved by any suitable means, as, for instance, by the fast and loose pulley gear 8 driving the pinion 9, carried by the casing and meshing with the gear 75 wheel 10 carried by the drum.

I claim:

1. An aerating apparatus for clothing comprising a revolving drum adapted to receive and confine clothing within it, means for forcing air through said drum and the 80 clothing contained therein, and bristles located within the drum in position to contact with and act upon the surface of clothing treated therein.

2. An aerating apparatus for clothing comprising a revolving drum, means for forcing air therethrough, and brushes located therein adapted to act upon the surface of the goods to be treated; said brushes being located to act as baffles and assist in 90 the tumbling of the goods in the drum.

3. An aerating apparatus for clothing comprising a revolving drum, means for forcing air therethrough, and brushes located therein adapted to act upon the surface of the goods to be treated; said brushes being provided with bristles and being free 95 to rotate.

4. An apparatus for air treatment of clothing or other like goods comprising a revolving drum, means for forcing air through the drum, and baffles in the drum having bristles thereon.

Signed at Oberlin, O., this 4th day of June, 1919.

HENRY FRAZEE, JR.
